Specification of Letters Patent

Patented Apr. 6, 1915.

Application filed December 3, 1910. Serial No. 595,473.

To all whom it may concern:

Be it known that I, ARTHUR H. GIBSON, a subject of the Crown of Great Britain, and resident of Easton, in the county of Northampton and State of Pennsylvania, have invented a new and useful Improvement in Mining-Machines, of which the following is a specification.

This invention relates to improvements in mining machines and is directed to machines which are well adapted for use in operating upon coal.

My invention relates more particularly to improvements in coal cutting and loading machines and contemplates the provision of a portable platform on which is mounted a coal puncher, a conveyer which extends beneath the platform to a point adjacent to the coal face for conveying the coal broken down by the puncher back to a point to the rear of the puncher, and a coal car operationally connected to the machine for receiving the coal from the conveyer.

The object of the invention is to provide certain improvements in the construction, form, arrangement and operation of the several parts of a coal cutting and loading machine whereby the efficiency of the machine is increased and the cutting, transfer and loading of the coal is facilitated to a material degree.

A practical embodiment of the invention is represented in the accompanying drawings in which,

Figure 1 represents the coal mining machine in side elevation in position for use, the front portion of the endless carrier being also shown. Fig. 1^a is a continuation of Fig. 1, showing the rear portion of the endless conveyer and also the car for receiving the coal therefrom. Fig. 2 is a plan view of the portion of the machine shown in Fig. 1, and Fig. 2^a is a plan view of the portion of the machine shown in Fig. 1^a. Fig. 3 is a detail cross section taken in the plane of the line A—A of Fig. 1, looking in the direction of the arrows, the portable platform being shown in cross section at that part where the rotary support for the puncher is mounted. Fig. 4 is a transverse section taken in the plane of the line B—B of Fig. 1, looking in the direction of the arrows. Fig. 5 is a transverse section taken in the plane of the line C—C of Fig. 1, looking in the direction of the arrows. Fig. 6 is a detail plan view showing the means for starting and stopping the mechanism for propelling the platform back and forth along the track. Fig. 7 is a detail section taken in the plane of the line D—D of Fig. 6, looking in the direction of the arrows. Fig. 8 is a detail section showing more clearly the winch engaging the chain for moving the platform back and forth along the track. Fig. 9 is a detail section on an enlarged scale, of the friction clutch connection between the platform propelling clutch and the motor. Fig. 10 is a detail horizontal section showing the means for adjusting the puncher longitudinally along its trunnions. Fig. 11 is an enlarged transverse vertical section taken in the plane of the line E—E of Fig. 1, looking in the direction of the arrows. Fig. 12 is a detail horizontal section taken in the plane of the line F—F of Fig. 11, looking in the direction of the arrows, illustrating the yielding worm gear mechanism for swinging the puncher horizontally. Fig. 13 is a detail view showing the yielding worm gear mechanism for swinging the puncher vertically. Fig. 14 is a detail section taken in the plane of the line G—G of Fig. 13, looking in the direction of the arrows. Fig. 15 is a detail side view showing the positions which the parts assume as the undercutting operation is about to start. Fig. 16 is a top plan view of the same. Fig. 17 is a detail view showing the positions of the parts after the undercutting operation has been completed and the knocking down operation commenced. Fig. 18 is a top plan view of the same, and Fig. 19 is a detail view of the removable bar for attaching the conveyer to the mining machine platform.

The track herein shown for the coal mining machine is formed in short sections comprising a series of cross ties 1 and the usual track rails 2. These track sections may be connected to each other by fish plates 3 and bolts 4 engaging the abutting ends of the adjacent track sections for forming a continuous track.

The portable platform of the coal mining machine is denoted by 5 and it is provided

2
 with two front feet 6 and two rear feet 7 arranged to slide along the track rails 2. Each of the two front feet 6 is connected to the platform 5 through the intermediary of a spring 8 and block 9, so as to permit the feet 6 to yield slightly with respect to the platform 5, to absorb vibrations of the platform due to the operation of the puncher. The two rear feet 7 are connected to the platform 5, at a single point, by providing the feet 7 at the ends of the yoke 10, which yoke is attached midway between its ends to a lug 11 on the platform 5, by a bolt 12, thus forming a three-point support for the platform 5. Sufficient lost motion is provided between the yoke 10 and platform 5, to enable the feet 7 to adjust themselves to inequalities in the track rails owing to the roughness of the mine floor, thus obviating the necessity of smoothing the mine floor to an accurate degree.

The coal puncher cylinder is denoted by 13, the front head by 14 and the pick by 15. This pick is operated in the usual manner by pressure fluid fed to the cylinder 13 from a main motive fluid supply pipe 15 through a flexible branch pipe 17. The coal puncher may be swung laterally into the different desired angular positions and held yieldingly in such positions by the following mechanism: A worm gear 18 of ring form is frictionally held between the cylinder support 19 and a ring 20, in the present instance, by providing a plurality of bolts 21 projecting from the ring 20 through the base of the support 19 and interposing springs 22 between the base of the said support 19 and the heads 23 of the said bolts 21. A ring 24 is secured to the platform 5 by screw-bolts 25 the inner edge of which ring overlaps the base of the support 19, for retaining the support in its position. A worm 26 is slidably mounted on a horizontal shaft 27 and meshes with the worm gear 18. This worm 26 is yieldingly held in its normal position by springs 28, 29, interposed between the worm 26 and the thrust bearings 30, 31. The worm 26, shaft 27, springs 28, 29 and thrust bearings 30, 31, are housed within a recess 32 in the platform 5 of the machine. The shaft 27 is driven from a suitable motor 33 mounted on the platform 5, through the following connections: The shaft of the motor 33 is provided with a pinion 34 which meshes with a gear 35 on a stud shaft 36 mounted on the platform 5. This stud shaft 36 has a sprocket and chain connection 37 with the shaft 27. The motor 33 is driven by pressure fluid fed through the branch pipe 17 from the main motive fluid supply pipe 15.

The puncher may be swung vertically into any angular position and held yieldingly in such position, by the following

mechanism: A worm gear 39 of ring form is frictionally held between one of the trunnions 40 of the puncher and an outer ring 41, in the present instance by providing a plurality of bolts 42 projecting from the trunnion 40 through the ring 41 and interposing springs 43 between the outer face of the ring 41 and the heads 44 of the said bolts 43. The trunnion 40 and the ring 41 with the frictionally clamped worm gear 39, are rotatably mounted in the side frame 45 of the cylinder support 19, and the other trunnion 46 is rotatably mounted in the side frame 47 of the support 19. A ring 48 is secured by screw-bolts 49 to the side frame 45 with its inner edge overlapping the ring 41, thus serving as a keeper for retaining the trunnions in their position in the side frames of the support 19. A worm 50 is slidably mounted upon a vertical shaft 51, which worm meshes with the worm gear 39. This worm 50 is yieldingly held in its normal position on the said shaft 51 by springs 52, 53, interposed between the said worm 50 and upper and lower ball thrust bearings 54, 55, respectively. The worm 50, shaft 51, springs 52, 53, and ball thrust bearings 54, 55, are locked in a recess 56 in the side frame 45. The shaft 51 is rotated by a hand wheel 57 through intermeshing pinions 58, 59. The worm shaft pinion 59 is fast on the worm shaft 51 and the hand wheel 57 and its pinion 58 are slidably keyed to a stud shaft 60 free to turn in a bearing 61 of a bracket 62. A clamp nut 63 engages the screw-threaded end 64 of the stud shaft 60 for locking and releasing the said shaft. When the shaft is released, the hand wheel 57 may swing the puncher to different positions and after the puncher has been swung to the desired position, the hand wheel 57, pinion 58 and shaft 60 may be locked against movement by the clamp nut 63.

The machine is adapted for movement back and forth along the track by the provision of the following mechanism: A rope or chain cable 65 is provided at its forward end with a hook 66 arranged to hook over the front end of one of the track rails 2. The rear end of this cable is provided with a bracket 67 which is secured to one of the track rails 2, by bolts 68, at a distance to the rear of the machine. Intermediate its ends, the cable 65 passes under two idler pulleys 69, 70, and over a driving pulley 71 of a power actuated winch. The shaft 72 of this pulley 71 has fixed thereto a gear 73 which meshes with a pinion 74 loose on a cross shaft 75. A friction or slip connection between the pinion 74 and the shaft 75, is provided by interlocking the pinion 74 with a disk 76 frictionally engaged between the inner and outer members 77, 78, of a fric-

tion clutch, the outer member 78 of which is keyed to the shaft 75. This shaft 75 is driven in either direction from a reversing motor 79, through a gear and pinion connection 80, 81. This motor 79 is driven by pressure fluid supplied from the main supply pipe 16, through the branch pipe 82. A hand lever 83 for starting the engine in either direction is normally returned to its neutral position by the provision of a double inclined faced block 84 engaging the said lever. The inclined faces of this block are so arranged that the operator will have to hold the lever in position for driving the motor in either direction. An automatic brake is provided for locking the machine against movement along the track when the operating lever 83 for the motor 79 is in its neutral position, and for releasing the machine when the lever for the motor is thrown into position for driving the motor in either direction. This brake comprises a rocking lever 85 hinged at 86 on the platform 5, one arm of which lever is connected to the motor operating lever 83 by an adjustable rod 87 and the other arm of which lever is provided with a wooden or other suitable brake block 88 arranged to engage the periphery of the gear 80. A spring 89 tends to draw the block 88 into frictional engagement with the periphery of the gear 80. The parts are so arranged that when the lever 83 is in its neutral position, the brake will be applied to the gear 80, and when the lever 83 is in either of its other positions, the brake will be released from engagement with the said gear.

The puncher is adjusted longitudinally with respect to its trunnions by providing the opposite sides of the cylinder 13 with series of holes 90 arranged to be brought into register with a series of holes 91 through the trunnions, so that bolts 92 may be passed through certain of the holes 91 into engagement with certain of the holes 90. This arrangement permits the puncher to be adjusted into position to properly balance it and also absolutely prevents any liability of the puncher sliding after it has once been adjusted longitudinally with respect to its trunnions.

An endless conveyer 93 is provided for transferring the coal broken down by the pick. This conveyer is supported intermediate its ends upon a frame 94 provided with traction wheels 95. This conveyer is driven from a motor 96 through a pinion 97, gear 98, sprocket wheel 99, chain 100 and sprocket wheel 101. This motor 96 is driven by pressure fluid fed from the supply pipe 16, through a suitable branch pipe 102. The conveyer comprises a horizontal portion arranged to extend along the track sections between the track rails 2 and an upwardly

and rearwardly extended portion for permitting a coal car 103 to be brought into position beneath the rear end of the conveyer for receiving the coal therefrom and transporting it to any desired point. For the purpose of moving the conveyer along between the track rails toward and away from the coal face, the front portion of the conveyer may be attached by a removable cross bar 104*, Fig. 19, to chains 104 or other suitable suspension devices depending from the front end of the platform 5, said cross bar passing through the holes 111* in the sides of the conveyer trough 111.

Manually operated means are provided for moving the coal car relatively to the conveyer. In the event that the car is to be moved rearwardly little by little from underneath the endless conveyer 93, for insuring a complete loading of the coal car, these means may be constructed, arranged and operated as follows: A cable 105 is provided at its free end with a hook 106 arranged to engage a pin 107 at the front end of the coal car 103. This cable leads first rearwardly around a pulley 108 carried by a rear extension 109 attached to the axle of the traction wheels 95, from thence the cable 105 leads forwardly around a pulley 110 secured to the endless conveyer trough 111. From thence the cable leads rearwardly to and around a winding drum of a windlass 112. A pawl 113 may be provided for preventing the unintentional release of the cable 105.

In the event that the coal car is to be moved forwardly little by little, the hook 106 of the cable 105 is engaged with the pin 107 and the cable leads from said hook directly forward to the pulley 110 instead of around the pulley 108.

For more readily transporting the mining machine from place to place, axles 114 are provided on to which may be placed traction wheels of sufficient size to lift the front feet 6 off from the track rails. For bracing the yoke 10 which carries the rear feet 7 of the platform 5, side bars 115* are provided, which side bars extend from the platform 5 to the sides of the yoke adjacent to the feet 7. These side bars permit a lateral yielding of the yoke yet prevent a longitudinal displacement thereof.

After the undercutting operation has been completed, the side plates 115 are inserted into position upon both sides of the conveyer trough 111 at the front end of the conveyer to assist in the transferring of the coal as it is knocked down at points beyond the sides of the trough, to be shoved on to the conveyer for transfer back to the mine car. To assist the operator in the proper manipulation of the puncher, a source of light is mounted on the puncher, which source of light may be a gas, electric or other lamp 116.

arranged to direct the rays of light on to that portion of the coal being struck by the pick 15.

To keep down the dust as much as possible, a water nozzle 117 is also attached to the pick so as to direct a stream or jet of water on to the portion of the coal being operated upon by the puncher pick 15. The water is supplied to this nozzle 117 through

10 a suitable pipe connection 118.

To keep the endless conveyer 93 in position as it travels from its front horizontal portion to its diagonal upwardly inclined rearward portion, angle plates 119 are secured along the inside of the trough 111 in position to overlap the said chains of the conveyer 93 for a considerable distance.

15 The cycle of operations is carried out as follows: The machine is moved up into position to start the undercutting operation as shown in Figs. 15 and 16, the conveyer being extended forwardly as far as possible without liability of being struck by the puncher.

20 As the machine is advanced during the undercutting operation, the machine will strike removable bolts 121 on the conveyer so that the further advance movement of the machine will also advance the conveyer at the same time so as to keep the front end of the 25 conveyer sufficiently in advance of the puncher to permit the ready shoveling of the coal onto the conveyer. The machine is prevented from accidentally running off the end of the track rails 2 by providing in the 30 hook 66 with a stop 120, which lies in the path of one of the puncher feet 6. After the undercutting operation has been completed, the machine will be moved back a predetermined distance along the track.

35 40 The chains 104 depending from the mining machine platform are then connected to the trough 111 of the conveyer by passing a bar through corresponding holes 111* and the chains 104. The machine is then moved forward together with the conveyer until the forward end of the conveyer has been brought to the end of the undercut. The machine is then disconnected from the conveyer and is moved rearwardly into position

45 50 for starting the knocking-down operation. The side plates 115 are then slid into position onto the sides of the conveyer trough. The puncher is then put into operation for knocking down the coal. The 55 sweeping movement of the puncher laterally back and forth over the side plates serves to assist in loading the coal into the conveyer. As the conveyer transfers the coal from the front to the back of the machine and from

60 there into the mine car, the mine car may be moved relatively to the conveyer so as to insure the even and complete loading of the car. When one car is filled, it is removed and an empty car placed in its position.

Before starting a new undercutting operation, the entry is preferably cleaned up of all loose coal and the coal is transferred by means of the conveyer back and into the mine car. The side plates 115 are then removed. The machine is again attached to the conveyer by means of the chains 104 and the movable bar and the conveyer and machine and the attached mine car are moved rearwardly until the forward end of the conveyer is back of the front end of the forward track section. The front hook 66 and the rear bracket 67 of the cable 65 are detached and an extra track section is laid in advance of the foremost track section and connected thereto. The hook 66 is then attached to the front end of the newly placed track section and the bracket 67 is again attached to the track rail at the proper distance to the rear of the machine. The conveyer and machine still in their connected arrangement are then again moved into the position first described for repeating the cycle of operations.

65 In the operation of the puncher it is frequently desirable that the puncher follow up a line of cleavage in the coal as the coal is cracking. This is accomplished readily in the present machine by the means for rapidly moving the machine forwardly along the track when so desired. If the puncher were not arranged so that it could follow up such a cleavage in the coal, then only small pieces of coal could be broken down at one stage of advance of the machine and the whole face of the coal would 70 have to be chipped off before the puncher could be moved forward to the next stage of advance.

75 80 By the use of a power operated winch for moving the machine toward and away from its work, I am enabled to not only move the machine rapidly and thus save a great deal of time, but am also enabled to overcome any obstructions which would be insurmountable in a manually operated winch, 85 and am also enabled to permit the machine at any time to rapidly and easily move the conveyer itself back and forth and when so desired the mine car also. Therefore, the use of a power operated advancing and retarding mechanism accomplishes a series of 90 results in a minimum time and thus insures a maximum amount of work in such time. Again, the entire cutter as herein shown and described will cause the entry to be cut very 95 straight which is a great advantage in mining. It will also permit the machine to be operated on what is commonly known as "the dip" where water collects in the heading and the machine can operate where there 100 is so much water that it would be necessary to pump the same out with other means of driving. Furthermore, the mounting of a

source of light on the puncher itself so as to move with the puncher and thus keep a beam of light directed on to the work operated upon by the puncher pick, materially 5 assists in the rapid and efficient operation of the puncher. Also by the mounting of the water jet upon the puncher so as to always direct the jet or stream of water onto the portion being operated upon by the 10 puncher pick, the dust is kept down and the work facilitated.

By the use of feet instead of wheels for supporting the portable platform, the platform may be moved more easily through 15 heaps of coal, thus saving power as the wheels tend to ride up on the coal, thus also causing the machine to leave the track rails and cause a considerable loss of time in replacing the machine on the track. Also an 20 unintentional movement of the platform along the track due to the vibration of the puncher is obviated. These feet also take up much less room than traction wheels where the greatest possible amount of room 25 is essential. The use of feet instead of wheels also prevents the liability of the operator's feet becoming crushed between the wheels and the track as the feet of the platform will serve to push the operator's foot 30 down and away rather than to ride over the same. The three-point support for the puncher platform enables the machine to stand firmly in position even though the track is laid directly upon the uneven floor 35 of the mine. The slight yielding movement of the front feet serves to absorb the vibration of the puncher to a material degree, and thus facilitates the effective operation of the puncher.

40 The device for locking the hand wheel which adjusts the vertical position of the puncher permits the puncher to be yieldingly held in any desired position without danger of slipping back to another position during 45 its operation.

The provision of the brake on the motor for propelling the machine back and forth along the track absolutely prevents the machine from slipping along the track during 50 the operation of the puncher and also serves to quickly stop the engine. The correlation between the brake and the motor controlling lever facilitates the quick and accurate control of the movement of the puncher along the track. The means for moving the coal 55 car with respect to the conveyer also facilitates the rapid and even filling of the coal car.

It will be seen that the shape of the rear 60 portion of the conveyer is such that it will break the force of the blow of the car 103 if the car should run into the conveyer when the machine is working down grade, the car having to lift the conveyer bodily before the

car can strike the axle of the traction wheels 65 95. This wedging action between the car and the conveyer serves to eliminate the liability of damage due to the car running into the conveyer.

What I claim is:

70

1. A track, a mining machine thereon, a conveyer located between the track rails and passing beneath the mining machine, means for connecting the conveyer to and disconnecting it from the mining machine and 75 means for moving the mining machine back and forth along the track either with or without the conveyer.

2. A mining machine including a puncher, manually operated means for swinging the 80 puncher into different vertical positions, means for holding the puncher yieldingly in such positions and means for locking said puncher swinging means against movement.

3. A mining machine including a puncher 85 and manually operated means for swinging the puncher vertically comprising a worm gear carried by the puncher, a yielding worm meshing with said gear, a worm shaft and means for locking the shaft against movement. 90

4. A mining machine including a support, trunnions rotatably mounted in said support, each trunnion having a series of holes along the same, a puncher having a series of 95 holes along its sides in register with the holes in the trunnions and bolts entering certain of said holes for locking the puncher to its trunnions in different longitudinal adjustments.

5. A track and a mining machine arranged to travel along the same comprising a platform having two front feet resting on the track and a yoke secured to the rear of the platform, said yoke having two feet resting 105 on the track and side braces leading from the sides of the yoke to the platform for holding the yoke in a longitudinal direction.

6. A track, a mine car thereon, a conveyer arranged to transport the minings to the 110 mine car and a mining machine arranged to travel back and forth along the track over said conveyer.

7. A track, a mine car thereon, a conveyer arranged to transport the minings to the 115 mine car and a mining machine arranged to travel back and forth along the track over said conveyer and means for connecting the mining machine to and disconnecting it from the conveyer whereby the conveyer may be 120 moved by means of the mining machine when so desired.

8. A track, a mine car thereon, a conveyer connected to the mine car and adapted to transfer the minings thereinto and a mining 125 machine arranged to travel back and forth along the track over the conveyer.

9. A track, a mine car thereon, a conveyer

⑥ connected to the mine car and adapted to transfer the minings thereinto, a mining machine arranged to travel back and forth along the track over the conveyer, and means for connecting the mining machine to and disconnecting it from the conveyer, whereby the conveyer and mine car may be moved by the mining machine when so desired.

In testimony, that I claim the foregoing as my invention, I have signed my name in presence of two witnesses, this first day of December 1910.

ARTHUR H. GIBSON.
